Primary Examiner — T Chase Nelson*Assistant Examiner* — Kelly L Gross(74) *Attorney, Agent, or Firm* — Kilpatrick Townsend & Stockton LLP(57) **CLAIM**

The ornamental design for an organ and tissue transport device, as shown and described.

DESCRIPTION

FIG. 1 is a perspective view of an organ and tissue transport device, showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines show portions of the organ and tissue transport device that form no part of the claimed design. The X-Therma branding and design and the TIMESEAL branding and design are trademarks of X-Therma, Inc. and are not a part of the claimed design.

1 Claim, 7 Drawing Sheets---
